BUTTON FEEDING DEVICE FOR SEWING MACHINES

Ernst Melzer, Berlin-Lichterfelde, Herbert Siegmund, Herford, and Georg Käle, Berlin-Lichterfelde, Germany

Application June 7, 1939, Serial No. 277,959
In Germany October 30, 1937

3 Claims. (Cl. 112—113)

This invention concerns an automatic button feeding device in machines for sewing on buttons.

Automatic feed devices are known, which have a funnel-shaped magazine or hopper with a cylindrical tubular extension. The internal diameter of the cylindrical tube corresponds to the diameter of the button. Below the bottom delivery opening of the cylindrical tube is disposed a guide plate. From this guide plate the buttons are introduced into a tongs arrangement and by means of this tongs arrangement they are brought below the needles of an automatic button sewing machine. Now since, as follows from the law of probabilities, it may frequently occur, that the buttons which are thrown haphazard into the funnel will, in passing through the cylindrical part, reach the guide plate in an incorrect position, the known arrangement is provided with a special turning device which turns the buttons which have fallen incorrectly before they are pushed into the tongs arrangement.

According to the invention the exceedingly complicated turning arrangement which does not always function reliably is avoided by the provision in the bottom outlet plane of the cylindrical tube of two pusher members which are capable of being moved in two different radial directions. These pusher members are controlled by cam drives in such a manner that the buttons which reach the guide plate in the correct position are pushed into gripping tongs, whilst the buttons which fall incorrectly are pushed off the guide plate. For controlling the pusher members separate feeler levers are provided.

A constructional example of the invention is illustrated in the accompanying drawing, in which

Fig. 1 shows a side view of the device diagrammatically.

Fig. 2 a portion of the same device with the bottom button in the wrong position.

Fig. 3 a partial plan view of the same device.

Fig. 4 a partial side view on line A—B of Fig. 3 and

Fig. 5 a portion of the feeler lever to a larger scale.

The device consists of a feed magazine comprising an upper funnel-shaped widening 2 and a cylindrical guiding part 3. At both sides, diametrically opposite one another, there are riveted to the cylindrical wall retaining hooks 4, the hook-shaped ends 5 of which are normally flush with the edge of the bottom opening of the cylindrical part 3. The hooks 4 consisting of

elastic material, when unstressed, recede so far that the buttons which are deposited in the funnel 2 and lie piled in the cylindrical guiding part with their main surface parallel can leave freely at the bottom, without being obstructed by the hooks.

Below the outlet opening of the guiding part 3, at a small distance from it, is a stationary guide plate 6, on which the buttons 7 falling out of the guiding cylinder 3 rest. After a button has fallen on the plate 6, the two hooks 4 are moved towards one another by means of two pressure applying pins 8 operated by an automatically acting mechanism, not shown in the drawing. At the same time the sharp ends of the hooks, which are bent over about at a right angle, can penetrate between the more or less rounded edges of the buttons, so that there is no danger of the hooks striking against the side of the buttons and not being able to enter between the button edges. The pile of buttons lying above the hooks, of which only three buttons are shown diagrammatically in the drawing, is thus prevented from dropping prematurely down as far as the guide plate 6.

In the guide plate 6 there is provided, concentric with the axis of the guiding cylinder, an opening 12, through which can pass the feeler head 11 of a two-armed feeler lever 10 which is arranged to rock about the pivot 9. Should the button 7 be in the correct position, that is to say, if its upper side be directed upwards, the feeler head 11 can enter so far into the opening 12 that it will be flush with the upper surface of the guide plate 6 (position shown in Fig. 1). In this position the other end of the feeler lever 10 is opposite the opening 13 of the driver 14. The driver 14 is fixed to the bar 16 of a pusher member 15 which is moved by way of a forked frame 17 by a cam disc 18, the roller 20 of the fork being pressed by a spring 19 against the cam disc 18.

The movement towards the left of the pusher member 15 can then take place without obstruction, since (as in the position shown in Fig. 1) the feeler arm 10 can pass through the opening 13 of the driver member 14. During this movement the button 7 is pushed between the tongs jaws 22, 23, which are acted on by the spring 28, and is held by them.

From below a part provided with two pins or prongs 27 is moved in the direction of the arrow α by any arrangement of a kind known per se in connection with automatic devices and not shown in the drawing. The pins are arranged

at the radial distance b of two holes 25 of the button and are capable of yielding in the axial direction in a manner known per se and not illustrated in the drawing, so that, when moving upwards and passing through the opening 24 in the lower jaw 22 of the tongs, the pins, if they should not by chance be in alignment with the two holes 25 and enter them, can yield resiliently.

The carrier 26 of the pins 27 thereupon forms a half revolution through 180°, during which the needles slide against the lower surface of the button, until the pin points penetrate into two oppositely disposed holes 25. During the continued rotation of the pin carrier 26 the button 7 is carried round, until, after completing the half revolution, it is taken into the desired position, in which the holes in the button have the correct position with respect to the needles of the sewing machine of a kind known per se, which is not shown in the drawing. The tongs arrangement with the button is only then brought under the button sewing machine and the button is automatically sewn on by it.

If, on the other hand, a button should have entered the guiding cylinder 3 in the wrong position and consequently have also reached the guide plate 6 in the wrong position (the position shown in Fig. 2), the head 11 of the feeler lever 10 can enter the depression 13a of the button, causing the feeler lever 10 to rock about the pivot 9, so that the outer lever end is swung out of alignment with the opening 13 in the driver member. When, during the rotation of the cam disc 18, the places of smaller radial distance become operative on the roller 20, the bar 16 of the pusher member can under the action of the spring 19 move to the left, but only by a quite small amount, until the feeler lever 10 strikes against the driver member 14 and is at the same time secured against slipping by the catch 21. In this way the pusher member 15 is prevented from moving, so that the button will not be pushed into the tongs arrangement.

This incorrectly placed button is then pushed by another pusher member 15a, which is arranged at about 90° to the sliding member 15 (Fig. 3), off the guide plate 6 into a receptacle (not shown in the drawing) and is transferred as required back to the funnel 2. The motion of this pusher member 15a is released by a feeler lever 10a which bears with its feeler end 11a against the end of the first-named feeler lever 10. In the position resulting from a button 7 falling incorrectly the supporting end 11a of the feeler lever 10a lies opposite the opening 13a of the driver member 14a, so that, when released by the cam disc 18a, the pusher member 15a will be moved by the spring 19a and will push away the incorrectly lying button (Fig. 4).

In order that this motion shall not be hindered by the feeler head 11 in the depression of the button, the head part 10b of the feeler lever 10 is drawn by a cam drive 29, a two-armed lever 29a and a link member 30 out of the depression. In order that during this movement the other lever arm of the feeler lever 10 may be enabled to remain behind the catch 21 of the driver member 14, the feeler lever 10 is made in two parts (see Fig. 5). The striking part of the feeler lever is provided at its pivot eye 31 with a finger 32, against which bears under the action of a spring 33 the feeler arm 10b of the feeler lever 10, which is capable of rocking about the same pivot pin 9. The spring is made of such strength that with normal feeling motions the entire feeler lever will

act in the manner of a rigid lever. Only when the cam drive 29 acts on the feeler lever arm 33 will the head part 10b be rocked with respect to the striking part of the feeler lever, the spring 33 being tensioned.

The lever 10a is made in two parts in a similar manner. It is normally held in the extended position exactly like the lever 10 by a spring 33a. The cam drive 29 (Fig. 2) moves with respect to the cam disc 18a in such a manner that the drawing downwards of the head part 10b of the lever 10 only commences, when the pusher member 15a has already moved a certain distance towards the button 7, without however having come in contact with the button. The result of this is, that the feeler end of the lever 10a will already have entered the opening 13a. On the head part 10b being drawn downwards by the cam disc 29 and the head part 11a of the lever being thereby rocked downwards, the movement of the pusher member 15a cannot be obstructed thereby, as the lever 10a is already in the opening 13a and is pressed by the spring 33a only against the upper edge of the opening 13a.

The result of this arrangement is, that only one of the pusher members alternately can each time be put in operation, whether the correctly placed button is pushed into the tongs arrangement or the incorrectly placed button is thrown off by the other pusher member.

What we claim is:

1. A device for feeding buttons having a depression on one side to a sewing machine or the like, comprising a hopper having a cylindrical part with an internal diameter corresponding to the diameter of the buttons, a guide plate disposed below the outlet at the bottom of said cylindrical part and having an opening therein, two pusher members disposed in the plane of said outlet and capable of moving in said plane in different radial directions for pushing the buttons deposited on the guide plate, a tongs arrangement for receiving the buttons from the guide plate and for holding said buttons in sewing position, and cam operated means for controlling the motion of said pusher members, the cam operated means of one pusher member including a two-armed feeler lever, a feeler head at the end of one arm of the lever, capable of contacting with the button through the opening in the guide plate, a spring attached to the pusher member, a stop member fixed to the pusher member and having a hole for the passage of the other arm of the two-armed feeler lever, whereby, when the button is in the correct position and the feeler head contacts with the flat side of the button, the lever arm can pass through the hole in the stop member and the pusher member can push the button into the tongs arrangement and, when the button is in the incorrect position and the feeler head enters the depression in the button, the lever arm will strike against the stop member and the pusher member will remain stationary.

2. A device as claimed in claim 1 in which the second pusher member is disposed substantially at right angles to the first-named pusher member and its cam-operated means includes a feeler lever adapted to be controlled by the feeler lever of the first-named pusher member, for the purpose of pushing incorrectly positioned buttons away from the tongs arrangement.

3. A device for feeding buttons having a depression on one side to a sewing machine or the like, comprising a hopper having a cylindrical part with an internal diameter corresponding to

the diameter of the buttons, a guide plate disposed below the outlet at the bottom of said cylindrical part and having an opening therein, two pusher members disposed in the plane of said outlet and capable of moving in said plane in different radial directions for pushing the buttons deposited on the guide plate, a tongs arrangement for receiving the buttons from the guide plate and for holding said buttons in sewing position, and cam operated means for controlling the motion of said pusher members, the cam operated means of one pusher member including a feeler device comprising two one-armed levers capable of swinging about a common pivot, a stop member on one of the one-armed levers and a spring capable of drawing the other one-armed lever against the said stop for holding the two levers in the extended position, a feeler head at the end of one of the levers, capable of contacting with the button

through the opening in the guide plate, a spring attached to the pusher member, a stop member fixed to the pusher member and having a hole for the passage of the other lever of the feeler device, whereby, when the button is in the correct position and the feeler head contacts with the flat side of the button, the said other lever can pass through the hole in the stop member and the pusher member can push the button into the tongs arrangement and, when the button is in the incorrect position and the feeler head enters the depression in the button, the said other lever will strike against the stop member and the pusher member will remain stationary.
